AERIAL PROJECTILE GAME

Hugo F. Rothe, Trenton, Mich.

Application June 23, 1944, Serial No. 541,745

3 Claims. (Cl. 273—95)

1

This invention relates to game apparatus comprising a net, game pieces adapted to seat in the meshes of the net and a mallet for projecting the game pieces upwardly and propel them across the net.

Game apparatus of a similar character has been proposed in which spherical game pieces or balls have been used but such apparatus requires little if any skill and is lacking in interest to the players.

It is an object of the present invention to provide game pieces designed to increase the skill required to project the game pieces across the net thus increasing the interest of the players.

A further object of the invention resides in providing game pieces in the form of trumpet shaped cups of round and polygonal contour in cross section, the cups of the same contour being adapted to nest one within the other while certain of the polygonal cups will nest in cups of a different polygonal contour.

Another object of the invention resides in providing apparatus for playing games which requires a high degree of skill to advance the game pieces affording the participants the greatest amount of entertainment.

Other objects and advantages of the invention will be apparent during the course of the following description.

In the accompanying drawings forming a part of this specification and in which like numerals are employed to designate like parts throughout the same,

Fig. 1 is a plan view of the net forming the game board,

Fig. 2 is a side elevation view of the game board showing the mallet in striking position,

Fig. 3 is a cross sectional view of the game board with the game pieces in playing position,

Fig. 4 is a side elevational view of the mallet,

Fig. 5 is a top plan view of the round game piece,

Fig. 6 is a vertical section taken on line 6—6 of Fig. 5, and,

Figs. 7, 8, 9, 10, 11, 12, 13 and 14 are plan views of the different polygonal shaped game pieces.

In the drawings, wherein for the purpose of illustration I have shown a preferred embodiment of my invention, the numeral 5 denotes generally a game board having its playing surface preferably formed of netting material fabricated from cord, wire, plastic or other suitable material. While a netting material is preferred it is apparent the game board may be made from a perforated sheet material and the term net is intended to cover all mesh or perforated mate-

2

rials. The netting material is supported in a rectangular frame 6 composed of side bars connected together by angular corner braces 7 to which are connected uprights or legs 8 for supporting the frame in an elevated horizontal plane above the table or other support on which the game board is placed. In actual practice it has been found desirable to have the game board elevated four inches or more above the table or support on which it is resting. The net is tied or otherwise secured to its supporting frame and is not stretched taut.

The game pieces comprise a plurality of cups 9, each of the cups being substantially trumpet shape with a wide upper end 10 and a narrow closed bottom end 11 which is slightly weighted. There are four sets of nine cups each and the cross sectional contour of the cups in each series varies. The contour of the cups is round, triangular, square, quintagonal, hexagonal, heptagonal, octagonal, nonagonal and dodecagonal as shown in Figs. 5 to 14 inclusive and designated by the numerals 9, 10, 11, 12, 13, 14, 15, 16 and 17 respectively. Each set of cups has a distinguishing color to identify one set from the other and an identifying number may be placed in the bottom of each of the polygonal cups to readily indicate the number of angles. All the cups owing to their tapered shape are adapted to nest in cups of the same cross sectional contour. The round cups can only nest in other cups of a corresponding contour while certain of the polygonal cups can nest in other cups of a different polygonal contour. For instance, the triangular cup can nest in the hexagonal, nonagonal, and dodecagonal cups, while the square cup can nest in the octagonal and dodecagonal cups and the hexagonal cup can nest in the dodecagonal cup. The cups are adapted to seat in the meshes of the netting with the flared upper end resting on the sides of the mesh and the lower end projecting below the netting, as clearly shown in Fig. 3.

The mallet for projecting the cups across the game board is shown in Fig. 4 and consists of an elongated head 18 of circular cross section having a handle 19 connected thereto in off-set relation to the center of the head. The relative long end of the head is the striking end and has its striking surface rounded, as at 20.

Various rules may be adopted when the apparatus is employed in playing a game. The game pieces or cups are seated in the meshes of the net 5 with the flared upper ends 10 resting on the sides of the mesh and the lower weighted ends 11

depending from the net. The player manipulates the mallet beneath the net so that the head 18 strikes the lower end of a cup to project the cup upwardly and project it across the board. The direction of flight of the cup will depend on the skill of the player in striking the cup with the mallet. The cups either seat in another mesh of the net or nest in one of the other cups and a skilled player may control the movement of the cups with a fair degree of accuracy.

One way in which the apparatus may be employed is what I call the game of advance. The players place their cups in the meshes of the net in a row parallel to and adjacent one of the sides of the frame. The object is for each player to project his cups across the net and line them up in the same order on the opposite side. If a player nests one of his cups in the cup of an opponent the opponent's cup must return to the starting position.

In a slightly modified form of game which I call the game of elimination the cups are lined up by the players in the same order as in the game of advance. The object of this game is to nest the cups in the cups of an opponent which are of the proper contour to receive the cup projected. When a cup is nested in an opponent's cup of the proper shape the opponent's cup is eliminated. Cups which are nested in an opponent's cups of the wrong shape must be returned to the starting position. When all the cups of an opponent have been eliminated the game is over, or if desired the various shaped cups may be given different values in points and each player adds up the points of the cups eliminated, the player having the highest score being the winner.

Another form of game is the game of king, in which the round cup is designated king. The object is to nest the king cup of a player in the king cup of an opponent. The game is played similar to the game of elimination in that the nesting of a cup in the cup of an opponent, of the proper shape, will eliminate the cup of the opponent. Improper nesting of a cup in the cup of an opponent will result in the opponent's cup being considered captive and it will remain captive until the upper cup's player separates the cups by striking them with the mallet. If there are three cups nested together the intermediate cup is eliminated from the game.

The games described in the foregoing are

merely illustrative and are subject to various modifications to increase the interest and skill of the players. It is apparent that game apparatus disclosed will require the exercise of the utmost skill of the players so that games may be devised which will be highly entertaining and amusing to the players.

Having thus described my invention, I claim:

1. The combination with a game board of perforated material and striking means, of a series of trumpet shaped game pieces of different cross sectional contour adapted to seat in the perforations of the game board with their lower ends depending from the game board for engagement by the striking means.

2. The combination with a game board of perforated material and striking means, of a series of trumpet shaped game pieces of different cross sectional contour adapted to seat in the perforations of the game board and nest in pieces of like contour, the lower ends of the game pieces depending from the game board for engagement by the striking means.

3. The combination with a game board of perforated material and striking means, of a series of trumpet shaped members of different cross sectional contour adapted to enter the perforations of the game board and supported therein by their flared upper ends with the lower ends in depending relation to the game board, certain of said members being adapted to nest in other of said members, said members being shifted over the surface of the game board by the striking means engaging the lower end of said members.

HUGO F. ROTHE.
